(57)

CLAIM

The ornamental design for a hammer, as shown and described.

DESCRIPTION

FIG. 1 is a right side perspective view of a hammer, according to an example embodiment of the present invention.

FIG. 2 is a right side view of the hammer shown in FIG. 1.

FIG. 3 is a left side view of the hammer shown in FIG. 1.

FIG. 4 is a top view of the hammer shown in FIG. 1.

FIG. 5 is a bottom view of the hammer shown in FIG. 1. FIG. 6 is a back side view of the hammer shown in FIG. 1; and,

FIG. 7 is a front side view of the hammer shown in FIG. 1. The broken lines are included for the purpose of illustrating an environment, and form no part of the claimed design.
